UNITED STATES PATENT OFFICE.

ABRAHAM FRIEDMAN, OF WORCESTER, MASSACHUSETTS.

DESIGN FOR A SOCIETY-EMBLEM.

48,106.

Specification for Design.

Patented Nov. 9, 1915.

Application filed August 14, 1915. Serial No. 45,597. Term of patent 3½ years.

To all whom it may concern:

Be it known that I, ABRAHAM FRIEDMAN, a citizen of the United States of America, residing at Worcester, in the county of Worcester and State of Massachusetts, have invented a new, original, and ornamental Design for Society-Emblems, (more particularly for the Young Men's Hebrew Association,) of which the following is a specification, reference being made to the accompanying drawing, forming part thereof.

The figure is a plan view of the society emblem, showing my new design.

I claim:—

The ornamental and figurative design for a society emblem as shown.

ABRAHAM FRIEDMAN.
